(57) **CLAIM**

The ornamental design for a robotic end effector, as shown and described.

DESCRIPTION

FIG. 1 is a perspective view of a robotic end effector; FIG. 2 is a front elevational view of the robotic end effector of FIG. 1;

FIG. 3 is a rear elevational view of the robotic end effector of FIG. 1;

FIG. 4 is a side elevational view of the robotic end effector of FIG. 1, as seen from what is the left side when viewed from the front;

FIG. 5 is a side elevational view of the robotic end effector of FIG. 1, as seen from what is the right side when viewed from the front;

FIG. 6 is a top plan view of the robotic end effector of FIG. 1; and,

FIG. 7 is a bottom plan view of the robotic end effector of FIG. 1.

The design is represented by solid lines in the drawings. The portions shown in broken lines do not form part of the design.
